Design No. 428
Furniture & Cabinet Manufacturer
Messrs. Backus, Bacon & Co., Book Store Design.

Patented September 1857.

Dec. 428

Jeremiah D. Green, of Troy, N.Y. assignor to
Buckus Bacon & Co
Letters Patent No 428. Dated, Dec. 9, 1851.

The schedule referred to in these Letters Patent and making part of the same.

To all to whom these presents shall come:

Be it known that I, Jeremiah D. Green, of Troy in the County of Rensselaer & state of New York, have invented or produced a new design of cook stove, & do hereby declare that the following is a full & exact description of the same, reference being had to the annexed drawing making a part of this specification, which is a perspective view of the stove.

The ornamental design of my stove consists of arabesque figures a, b, c, d & e, disposed upon the door and front panels, which are formed by mouldings f, f, & g, and also the ornamental feet, as represented.

What I claim and desire to secure by letters
patent is the ornamental design & configuration of cook stove, substantially, the same as described & represented in the annexed drawing.

Witnesses.
